UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

RIBBON MECHANISM.

Application filed July 25, 1922. Serial No. 577,360.

To all whom it may concern:

Be it known that I, MANSFIELD C. CRAWLEY, a citizen of the United States of America, and a resident of Groton, county of 5 Tompkins, and State of New York, have invented certain new and useful Improvements in Ribbon Mechanisms, of which the following is a full and clear specification.

This invention has for its object to provide 10 a simple mechanism for reversing the direction of wind of the ribbon upon exhaustion of the ribbon from one of the spools and also a simple mechanism for actuating the ribbon feed from a power-driven type-bar actuator, 15 as more fully hereinafter set forth.

In the drawing—

Fig. 1 is a vertical sectional view of a motor-operated typewriting machine showing my invention applied thereto;

20 Fig. 2 is a transverse sectional view showing the ribbon-reverse mechanism;

Figs. 3, 4 and 5 are views showing details of the reversing mechanism;

Fig. 6 is a plan view partly in horizontal 25 section showing my invention applied to a motor-operated typewriting machine;

Figs. 7 and 8 are vertical sectional views showing the ribbon-feed mechanism in different positions;

30 Fig. 9 is a view showing details herein-after described.

Referring to the four sheets of drawing annexed, 10 designates an electric motor mounted at the rear of the machine and belted to a pulley 11 affixed to a counter-shaft 12. This shaft 12, through suitable mechanism, such for instance as shown in my former Patent No. 1,156,061, is adapted to pull back a type-bar actuator consisting, generally, of an arcuate bar 13 mounted to swing fore and aft on pendant arms 14, a coil spring 15 being provided for throwing the type-bar actuator forwardly when the hold-back latch is released by a key in the keyboard, as more fully set forth in the aforesaid patent.

Attached to the type-bar actuator is the rear end of a link 16, this connection being by means of a pendant arm 17 pivotally mounted on the tensioning shaft 18 of the actuating spring 15 and rigidly connected to one of the adjacent swinging arms 14 of the actuator, so that the link 16 will partake of the fore-and-aft movement of the type-bar actuator. The forward end of the link

16 is pivotally connected to the upper end of a lever 19 carrying a pawl 20 which is adapted to normally engage the teeth of a ratchet wheel 21, this ratchet wheel being affixed to the transverse ribbon-feed shaft 22. The feed takes place on the return, non-working stroke of the type-bar actuator, thereby putting upon the electric-motor mechanism the work of feeding the ribbon, this being desirable because of the fact that it relieves the spring-actuated, forward, working stroke of the actuator of the duty of feeding the ribbon and thus contributes to uniformity of printing.

The feed shaft 22 is adapted to slide longitudinally in its bearings 23 and carries a pair of crown-gears 24, one at each side of the machine, with teeth facing outwardly toward the respective sides of the machine. Adapted to mesh with the gears 24 is a pair 75 of similar gears 25, one being affixed to the lower end of each of the spool-shafts 26, the teeth of these gears 25 facing downwardly. The teeth of the gears 24 and 25 are not bevel-gears, but are in the form of pins, 80 so as to thereby eliminate all tendency while in mesh to either remain in mesh or to demesh by a thrust action, whereby the gears may be demeshed at one side and meshed at the other side by a slight endwise thrust on 85 the shaft 22.

Pivoted on the frame of the machine, under each spool, is a vertical lever 27 whose upper end is forked so as to straddle the ribbon, and affixed to the ribbon, near each end thereof, is a button or other obstruction 28 which, when the ribbon is exhausted from the spool, will contact with the forked-end of the lever and swing the lever toward the opposite side of the machine. The lower 95 ends of the levers 27 are connected by a downwardly-bowed rod 29 which is pivotally connected to a link 30.

The bar 29 is adapted to operate, through the medium of said link 30, a reversible 100 thrust device preferably constructed as follows: The free end of the link 30 is pivotally connected at 31 to the rear, free end of a snap-over lever 32 whose forward-end is pivotally connected to a bracket 33 stationarily affixed to the frame of the machine. The lever 32 desirably consists of a sheet-metal yoke whose flat arms embrace two stationary flat plates 34 formed on said bracket 33, the forward-ends of the arms of the yoke 110

being pivotally connected to the plates 34 at 35. Pivotally mounted between the plates 34, at their rear ends, i. e., at a point 36', directly to the rear of the pivot 35, is the 5 rear-end of a lever 36 whose forward-end is formed into a fork 37 whose forward-ends engage in a groove 38 of a collar affixed to the shaft 22. This lever 36 is desirably stamped up from sheet-metal, the rear- 10 wardly extending part consisting of two plates adapted to nicely fit against the inner faces of the stationary plates 34. The bar 30 is also desirably made of sheet metal, provided with flat, rearwardly projecting 15 ears 39 which fit between the arms of the lever 32. By reason of thus making the various parts of this mechanism of flat pieces fitting against each other flatwise, the parts are guided and supported in their 20 movements, the pivots being thereby relieved of strain, making the mechanism durable and easy to operate. Connecting the fork lever 36 to the outer end of the snap-over lever 32 is a retractile coil spring 40, 25 the points of connection of this spring being such that as the snap-over lever 32 is swung back and forth the spring will pass back and forth across the center of the pivotal point 36' of the fork lever.

30 When one of the buttons 28 swings its adjacent fork lever inwardly, the bar 29 will be moved endwise in the opposite direction and thus swing the snap-over lever 32 to the limit of its movement in the same direction. This movement of the snap-over lever 32 reverses the direction of pull of the spring 40 and thus, by a quick, snap-over action, reverses the direction of the thrust of the fork 37 on the shaft 22. The spring 40 is strong enough to pull the shaft to one side or the other, according to which position it is shifted to. It will thus be seen that when the spring 40 is thus snapped over center and the direction of thrust of the 45 fork is thus reversed, the feed shaft 22 will be instantly shifted over to bring its opposite pair of gears into mesh and these opposite gears will be held in mesh until the direction of thrust of the fork 37 is again shifted by the operation of the button at the 50 opposite side of the machine. It will be noted that the type of spring I employ and its arrangement in a snap-over reversing device is such that the reversing action is accomplished by merely distending the spring far enough to permit the snap-over lever 32 to pass over center. The power thus required for slightly distending the spring is so little as to exert no appreciable pulling 55 effect on the ribbon, while at the same time the power of the spring after reversal is amply sufficient to not only slide the feed shaft 22 but hold the gears in mesh until the spring is again reversed.

60 It will thus be seen that in its preferred 65

form the invention lies in the idea of, first, employing a thrusting device requiring but a slight exertion of power to reverse it, and, secondly, accomplishing this reversing action by direct connection with the ribbon, 70 i. e., without directly pulling or pushing the shaft 22 but leaving that work to be done by the thrust-spring. It will be understood also that it is not absolutely necessary that the shaft 22 shall be shifted the instant the 75 thrust device is reversed, since with certain types of gears or if the bearings of the shaft 22 are dirty or rusted, the reversal of the shaft might be delayed until it is subsequently jarred by being stepped around one 80 or more times through the medium of the ribbon-feed mechanism. By the use of the pin crown gears, however (by which all tendency of the gears to demesh or stay in mesh is neutralized), the shifting action will 85 take place instantly the snap-over spring passes over center 36'.

It will be observed further that when the spring 40 passes over center, it not only reverses the thrust of the fork 37 but also 90 exerts its force to move the connecting-rod 29 in the direction of the movement of the rod. This action results in quickly throwing the forked-end of the lever 27 that is in action away from the button on the ribbon, whereby the feeding of the ribbon may continue in the same direction a limited distance before the button can again come into contact with the fork. This will give ample 95 time for accomplishing the reversal of the 100 gearing before the button again contacts with the fork, thereby making it doubly sure that destructive strain on the ribbon will be avoided.

This application is a substitute in part 105 for my co-pending application Serial No. 188,773, filed August 29, 1917.

What I claim is:

1. In a typewriting machine, a motor-actuated type-bar actuator-bar suspended on 110 depending arms, a ribbon-feed mechanism embodying a ratchet device, and a rearwardly-extending link connecting said ratchet device to one of said depending arms, whereby the reciprocation of the actuator-bar by the motor will operate the ratchet 115 ribbon-feed.

2. In a typewriting machine, a type-bar actuator embodying a transverse shaft and a pair of depending arms carrying the actuator bar, an arm pivotally mounted on said shaft and connected to one of said depending arms, a ratchet ribbon-feed device, and a link pivotally connecting the arm pivotally mounted on the shaft to said ratchet device. 120

3. In a typewriting machine, a ribbon-feeding mechanism embodying a transverse endwisely-shiftable shaft carrying gears, a spring-actuated reversible snap-over device connected to this shaft at one end, a link 125 130

5 pivotally connected at one end to the other end of said snap-over device, a bar extending transversely of the machine and pivotally connected to the other end of said link, and
5 a pair of ribbon-actuated levers pivotally mounted on the machine frame and having their lower ends pivotally connected to the ends of said bar.

4. In a typewriting machine, a ribbon-feeding mechanism embodying two sets of gears and an endwisely-movable drive-shaft carrying the driving gear of each set, said drive-shaft being adapted to be rotated by the writing machinery, a ribbon-reversing mechanism embodying thrust means adapted to resiliently force the shaft in one direction or the other and consisting of a snap-over lever having one end pivoted to the frame of the machine, a fork-lever likewise pivoted to the frame of the machine at a point adjacent to the pivot of the snap-over lever, this fork-lever being unconnected to said snap-over lever, a retractile spring connecting the snap-over lever to the fork-lever, and means actuated by the ribbon for reversing said thrust means.

5. In a typewriting machine, a ribbon-feeding mechanism embodying two sets of gears and an endwisely-movable drive-shaft carrying the driving gear of each set, said drive-shaft being adapted to be rotated by the writing machinery, a ribbon-reversing mechanism embodying thrust means adapted to resiliently force the shaft in one direction or the other and consisting of a snap-over lever having one end pivoted to the frame of the machine, a fork-lever likewise pivoted to the frame of the machine at a point adjacent to the pivot of the snap-over lever, this fork-lever being unconnected to said snap-over lever, a retractile spring connecting the snap-over lever to the fork-lever, and means actuated by the ribbon for reversing said thrust means embodying a laterally-movable member pivotally connected to the free end of the snap-over lever.

6. In a typewriting machine, a ribbon-feeding-and-reversing mechanism embodying two pairs of gears, one of which is car-

ried on an endwisely-movable drive-shaft, a reversible snap-over thrust device to hold the drive-shaft in either of its two driving positions and ribbon-actuated means for reversing said thrust device, said thrust device embodying a pair of separated supporting-plates 34 mounted on the frame, a snap-over lever 32 embodying two plates pivotally mounted on said supporting-plates and embracing the outer faces thereof, a fork-lever pivotally mounted on said supporting-plates and consisting of two separated plates lying between said supporting-plates, and a contractile spring connecting the fork-lever to the outer end of the snap-over lever and housed within the plates constituting said levers.

7. In a typewriting machine, a ribbon-feeding mechanism embodying two sets of gears and an endwisely-movable drive-shaft carrying the driving gear of each set, said drive-shaft being adapted to be rotated by the writing machinery, a ribbon-reversing mechanism embodying thrust means adapted to resiliently force the shaft in one direction or the other and consisting of a snap-over lever having one end pivoted to the frame of the machine at a point adjacent to the drive-shaft, a ribbon-actuated means connected to the free end of said snap-over lever, another lever carrying a fork at one end adapted to engage the drive-shaft and having its other end pivoted to the frame at a point farther away from the shaft than the pivotal point of the snap-over lever, and a retractile spring connecting the outer free end of the snap-over lever to the fork-carrying lever.

8. In a typewriting machine, a motor-actuated swinging actuator-frame embodying a type-bar actuator-bar, a ribbon-feed mechanism embodying a ratchet device, and a link connecting said ratchet device to one of the swinging parts of said actuator-frame, whereby reciprocation of the actuator-frame by the motor will operate the ratchet ribbon-feed.

In testimony whereof I hereunto affix my signature.

MANSFIELD C. CRAWLEY.
